[57] CLAIM

The ornamental design for an integrant gasoline pump
nozzle trigger holder and ice scraper, as shown.

DESCRIPTION

FIG. 1 is a front elevational view of an integrant gasoline pump nozzle trigger holder and ice scraper showing my new design;

FIGS. 2 and 3 are respectively top and bottom plan views thereof;

FIGS. 4 and 5 are respectively left and right side elevational views thereof;

FIG. 6 is a rear elevational view thereof; and

FIG. 7 is a perspective view thereof.

FIG. 6

FIG. 7
